UNITED STATES PATENT OFFICE.

EDWIN R. ANGELL, OF OREGON CITY, OREGON.

ANTIDRAFT.

Application filed February 27, 1922. Serial No. 539,531.

To all whom it may concern:

Be it known that I, EDWIN R. ANGELL, a citizen of the United States, and a resident of Oregon City, county of Clackamas, and 5 State of Oregon, have invented a certain new and useful Improvement in Antidrafts, of which the following is a specification.

The object of my invention is to provide 10 cheaper and more effective means for closing the apertures in the floor boards of an automobile thru which the lever brakes operate.

It has long been a problem to prevent the 15 heat of an engine in summer time and the cold air in winter, dust and dirt and obnoxious fumes at all times from passing thru the floor boards and into the body of the car.

By my invention I have provided a system 20 of brushes which will close the aperture immediately after the lever has been passed thru and will maintain a complete seal for a comparatively long period of time. All of these points and others I have shown in the following drawings, in which:

25 Fig. 1 is a perspective view showing my invention applied to the foot pedals of an automobile with a part broken away to show the center set of brushes in the aperture. It can readily be seen that the brushes will 30 close immediately after the pedal has passed and provide a seal immediately before it;

Fig. 2 is a cross sectional view taken on the line 2—2 of Fig. 1 and shows the construction of the brushes with a wooden 35 spacer in between the separate rows of brushes;

Fig. 3 is a cross sectional view taken on the line 3—3 of Fig. 1 and shows how the plate forms are locked with each other;

40 Fig. 4 is a perspective view of an individual brush unit;

Fig. 5 is a plan view of a single set of brushes with parts broken away to show inside details and illustrates how the emergency brake of an auto can readily pass 45 thru the brushes and they can still maintain a close seal to prevent a draft or any dust from entering into the car; and

Fig. 6 is a cross section detail view taken 50 on the line 6—6 of Fig. 5 and shows some other details of construction.

The brushes are made in single units. The bristles *a* are preferably made with a spacer *b* between the separate layers so that 55 there is no bulging as there would be otherwise. They are compressed and held in

place by means of a metal strip *c* which holds the bristles in place against the spacer strips. In the construction shown in Fig. 1 a stamped form *d* is made which has apertures *e* which are spaced so as to accommodate the movement of the pedals. A smaller piece of formed material *f* closes the end of the apertures in this particular design and holds the form plate *d* in place and prevents 60 it from spreading apart. The whole plate *d* is fastened to the car boards by means of screws or nails *g*. The single plate *h* shown in Fig. 5 containing an aperture *i* can be fastened to the floor boards with screws *j* 65 or the like. The apertures *e* and *i* are so spaced that the pedals *k* will pass down the center lines *s* which separate the ends of the two separate brushes of the set. The apertures *e* extend a trifle longer than the length 70 of the motion of the pedals *k* so that there are always brushes beyond the end of travel of the same. It can readily be seen by looking in the single unit apertures *i* which is shown in Fig. 5, that the lever *l* will pass 75 directly on the center line between the faces of the brushes and thus a minimum amount of wear will be effected on both of the brushes. There will also be no sagging or distortion of the bristles and thus my improved aperture closing device will be effective for a considerable period of time. This 80 has been the trouble with other devices which attempt to eliminate the draft as soon as they become distorted and worn and 85 therefore do not effectually prevent the objections which they were designed to do.

I claim:

1. In an automobile vehicle in which the floor boards have apertures in which levers 95 work, a plurality of brush units, each unit separate, the brush units positioned so that the faces of two brushes abut on the center line of travel of said lever in said aperture, two brush units constituting a set to close 100 a single aperture, sets of brushes held in position and enclosed by metal forms having suitable openings, and means for fastening said forms to the floor boards.

2. In an automobile vehicle in which the 105 floor boards have apertures in which levers work, a plurality of brush units, each unit separate and bound with a metal strip and the rows of bristles separated by spacers, the brush units positioned so that the faces of two 110 brushes abut on the center line of travel of said lever in said aperture, two brush units

constituting a set to close a single aperture, sets of brushes held in position and enclosed by metal forms having suitable openings, and means for fastening said forms to the 5 floor boards.

3. In an automobile vehicle in which the floor boards have apertures in which levers work, a plurality of brush units, each unit 10 separate and bound with a metal strip and the rows of bristles separated by spacers, the brush units positioned so that the faces of two brushes abut on the center line of travel of said lever in said aperture, an even number of brush units constituting a set to close 15 a single aperture, sets of brushes held in position and enclosed by metal forms having suitable openings, and means for fastening said forms to the floor boards.
4. In combination with the foot pedal of 20 an automobile, and the foot board having slots through which the said pedals extend, a frame extending around the slots in the foot board, a series of flexible bristles secured to the frame and covering the said slots.
5. In combination with an automobile foot 25 pedal extending through a slot in the foot

board of an automobile, a frame secured to the foot board around the said slot, bristles secured to the said frame at the longitudinal sides thereof and extending in opposite directions toward each other to meet in the center of the said slot whereby the slot is normally covered, the said foot pedal extending through the slot and thereby displacing certain of the said bristles. 30 35

6. A device of the character described comprising a rectangular frame, bristles secured to opposite sides of the frame and extending toward the center thereof, the free ends of the bristles meeting in the center of 40 the frame, and means to hold the said frame in position.

7. A device of the character described comprising a rectangular frame, bristles secured to opposite sides of the frame and projecting toward the center thereof, whereby the open center of the said frame will be closed by the said bristles, means to secure one end of the frame stationarily in position, and means to maintain the opposite end of 45 50 the frame in position.

EDWIN R. ANGELL.
